UNITED STATES PATENT OFFICE.

HOWARD D. COLMAN, OF ROCKFORD, ILLINOIS, ASSIGNOR TO HOWARD D. COLMAN, LUTHER L. MILLER, AND HARRY A. SEVERSON, COPARTNERS DOING BUSINESS AT ROCKFORD, ILLINOIS, AS BARBER-COLMAN COMPANY.

BOBBIN-HOLDER.

1,201,998.

Specification of Letters Patent. Patented Oct. 17, 1916.

Application filed February 1, 1915. Serial No. 5,562.

To all whom it may concern:

Be it known that I, HOWARD D. COLMAN, a citizen of the United States, residing at Rockford, in the county of Winnebago and 5 State of Illinois, have invented certain new and useful Improvements in Bobbin-Holders, of which the following is a specification.

This invention relates to devices for holding yarn masses, as for example, bobbins of 10 warp yarn; and one of the objects of the invention is to provide holders which may be conveniently operated to discharge the bobbins.

The invention has special, although not 15 exclusive, reference to bobbin-holders adapted for use in automatic winders, a particular object being to provide bobbin-holders which may be operated by mechanical means to discharge the bobbins.

20 In the accompanying drawings, Figure 1 is a fragmental view of an automatic winder provided with bobbin-holders embodying the features of this invention. Fig. 2 is a front view of the bobbin-holders looking in the 25 direction of the axis of the bobbins. Fig. 3 is a sectional view taken in the plane of dotted line 3 of Fig. 1. Figs. 4 and 5 are views taken in the planes of dotted lines 4 and 5—5, respectively, of Fig. 1. Fig. 6 is 30 a fragmental view, on a reduced scale, showing the winding mechanism.

In Patent No. 1,175,710, March 14, 1916, I have disclosed an automatic winder comprising a plurality of winder units, each 35 unit comprising means for supporting and rotating a cheese, and two bobbin-holders, one located above the other. One of the bobbin-holders supports the bobbin being 40 unwound, and the other bobbin-holder supports a reserve bobbin. The spent bobbin is withdrawn by the operative and a new or reserve bobbin substituted therefor. The bobbin-holders thus alternate in supporting the reserve bobbin. To save labor, it is 45 desirable to provide automatic means for discharging the spent bobbin.

In order that such mechanism may be as simple as possible, it is desirable that the spent bobbin be always in a particular one of the pair of 50 bobbin-holders. It also is desirable that the reserve bobbin be placed in a particular one of the pair of bobbin-holders, in order that the operative shall not need to consider in which holder to place the bobbin,

and may thus acquire speed in the performance of the bobbin-supplying operation. I, therefore, have provided above the bobbin-holder a support into which the reserve bobbin is placed by the operative, the active bobbin being contained within the bobbin-holder, mechanism being provided for discharging the spent bobbin from the bobbin-holder, and for discharging the reserve bobbin from said support to the bobbin-holder.

In Fig. 6 is indicated one form of winding mechanism that may be used. A is the yarn mass being formed and B is a device for rotating said yarn mass and for traversing the yarn. C is a clamp to hold the end of 70 the thread of the reserve bobbin. These parts may be similar to those shown in my said application Serial No. 628,474.

For convenience in manufacturing and assembling the winder, the winder units may 75 be grouped to form a plurality of bays. The pairs of bobbin-supporting devices of each bay may have a common supporting framework which may comprise a front angle plate 1 and a rear plate 2 rigidly connected 80 together by a suitable number of braces 3. Fixed to the angle plate 1 is a series of brackets 4, one for each pair of bobbin-supporting devices. The supporting frame formed by the parts 1, 2, 3 and 4 may be 85 attached to the framework of the winder in any suitable way; for example, certain of the brackets 4 may be secured, as at 5, to the brackets 6 that support the reserve thread-end clamps C; and upon the rear side of the 90 plate 2 may be secured pairs of lugs 7 and 8, each pair adapted to receive a hanger 9 arranged to be supported upon one of the longitudinal beams 10 of the winder framework. The lug 7 rests upon a nut 11 turned 95 on the lower end of the hanger 9, whereby the position of the group of bobbin-supporting devices may be properly adjusted at the time of erecting the winder.

In the construction herein shown, the reserve bobbin-support 12 comprises a sheet metal pocket 13 having at one side an upwardly extending wall 14, said wall being fixed to a pivot 15 which is journaled in the supporting frame. The pivot 15 extends 105 lengthwise of and above the pocket, so that gravity shall tend to hold the pocket in the position shown in Fig. 3. As shown in Fig.

2, the pivot 15 extends adjacent to the vertical plane of the axis of a bobbin lying in the pocket 13.

16 is a stationary strip of metal extending 5 lengthwise of the bobbin-support and serving as a stop for the wall 14 and thus determining the normal position of the pocket. The strip 16 also serves to prevent lateral displacement of the bobbin when the pocket 10 13 is swung upwardly.

A plate 17 extends lengthwise of the plate 2 behind the pockets 13, the plate 17 being spaced from the plate 2 by a bar 18. The rear end of the strip 16 is fixed to the plate 15 17. At the side of the pocket opposite to the strip 16 is a strip 19, the rear end of which is secured to the plate 17. The rear portion of the strip 19 is bent as at 20 to guide the butt end of the bobbin toward the 20 left-hand side of the pocket and thus assist to keep the reserve bobbin away from the running thread, as will appear more fully hereinafter. If desired, the strips 16 and 19 may be integral at their forward ends and 25 may be bent to form guides 21 to facilitate the insertion of the reserve bobbins.

Rigid with the forward end of the pivot 15 is a crank-arm 22 which extends into the path of movement of an inclined or cam member *a* on the traveling mechanism (not 30 shown) of the winder. When said cam member reaches the crank-arm 22 of a unit, the arm is raised to withdraw the pocket 13 from beneath the reserve bobbin, thereby 35 discharging said bobbin laterally into the bobbin-holder for the active bobbin, the spent bobbin having previously been discharged from the active bobbin-holder.

The active bobbin-holder 23 may be of any 40 suitable construction, that herein shown being generally similar to the bobbin-holder shown in Patent No. 1,045,879, dated December 3, 1912. In the present construction the active bobbin-holder comprises two parallel rods or wires 24, the forward portions of said rods being fixed to a pivot 25. The ends of the pivot 25 rest in bearing sockets 26 in adjacent brackets 4. The wires 24 support a loop or pocket 27 of flexible material 50 having a smooth inner side, as for example, muslin coated with oxidized linseed oil. The normal position of the wires 24 and the loop 27 is determined by contact of the rear ends of the wires 24 with the lower flange of 55 the plate 17, the wires being yieldingly held in such position by means of a tension spring 28 connected at one end to the forward end of one of the wires 24 and at its other end to a suitable fixed point. Any suitable 60 means may be used to provide a back stop for the bobbin; herein is shown a hardened-metal wear-plate 29 detachably secured to the plate 2. In the present embodiment of the invention, the entrance of the bobbin-holder 65 is the open upper side thereof. The

projecting forward end 24^a of one of the wires 24 constitutes a lever arm lying in the path of an inclined or cam member *b* of the traveling mechanism hereinbefore referred to. When the cam member *b* engages 70 the arm 24^a, the loop 27 is tilted downwardly and rearwardly, whereupon the spent bobbin slides longitudinally out of the loop. Preferably a conveyer 30 is provided below the bobbin-holders to carry the empty bobbins 75 to any desired point.

31 and 32 are guide plates to assist in directing the bobbins to the conveyer 30.

The bobbin-support 12 and the bobbin holder 23 are inclined so as to support the 80 bobbins at right angles to the average direction of the running thread. As indicated in Fig. 1, the plate 17 spaces the reserve bobbin away from the wall 2, and therefore when the reserve bobbin is discharged into the 85 bobbin-holder 23, the bobbin drops approximately vertically.

By reference to Figs. 2 and 3, it will be noted that the pocket 13 is above and slightly at one side of the loop 27 thereby leaving 90 space between the strip 19 and the edge 13^a of the pocket 13 for the passage of the running thread. The concave form of the pocket 13 keeps the reserve bobbin out of contact with the thread. 95

33 is a stationary curved guard plate covering the pivot 25 at the entrance to the reserve bobbin-support.

34 is a conveyer running along the front side of the row of bobbin-holders, for carrying 100 full bobbins within convenient reach of the operatives.

Assuming that there is a reserve bobbin in the bobbin-support 12, the end of the thread on said bobbin being held in the reserve thread-end clamp C, and that a bobbin in the bobbin-holder 23 is being unwound, the operation is as follows: At the proper time in the operation of the winder, usually shortly after the bobbin in the bobbin-holder 23 has been substantially or wholly unwound, the traveling mechanism reaches the unit, and the cam member *b* tilts the loop 27 downwardly, thus discharging the exhausted bobbin onto the conveyer 30. As soon as the cam *b* has passed the arm 24^a, the spring 28 restores the loop 27 to its normal position. The end of the reserve thread having been tied to the exhausted thread, the cam *a* reaches the 110 crank arm 22, and swings the pocket 13 upwardly, thereby discharging the reserve bobbin into the bobbin-holder 23. The fall of the bobbin into the bobbin-holder 23 assists to take up slack in the united threads. As 115 soon as the cam *a* has passed the crank arm 22, gravity restores the pocket 13 to its normal position. The operative, following the traveling mechanism, takes a full bobbin 120 from the conveyer 34, unwinds a little of 125 the thread, and places it in the bobbin-holder 23. The cam *a* then reaches the crank arm 22, and 130

the yarn, places the bobbin in the bobbin-support 12, and inserts the end of the yarn in the reserve thread-end clamp.

It will be noted that the bobbin is inserted into the active bobbin-holder 23 from above, thus removing the possibility of damage to the loop 27 through careless insertion of the bobbin through the front end of the loop 27, as in the bobbin-holder shown in the patent hereinbefore mentioned.

It will be noted that the plate 1 extends in front of the forward end of the loop 27, thus preventing the bobbin from jumping out of the pocket during the unwinding operation.

I would have it understood that the invention is not limited to the details and arrangement of parts herein shown, as various modifications may be made without departing from the scope of the invention as set forth in the appended claims.

I claim as my invention:

1. A winder having, in combination, a side-delivery bobbin-holder adapted to rotatably support a warp bobbin while being unwound, said bobbin-holder having an open upper side, and a bobbin-support pivotally suspended above the bobbin-holder upon an axis extending adjacent to the vertical plane of the axis of a bobbin lying on the support, the latter being arranged to swing out of supporting position to allow the bobbin to fall through the open upper side of the bobbin-holder.

2. A winder having, in combination, a side-delivery bobbin-holder adapted to rotatably support a warp bobbin while being unwound, said bobbin-holder having an open upper side, and a bobbin-support arranged to swing away from a position above the bobbin-holder to uncover the upper side of the bobbin-holder and to discharge a bobbin into the bobbin-holder.

3. The combination of a bobbin-holder, a bobbin support located above the bobbin holder and arranged to swing out from beneath a bobbin placed on the support, and a guide to facilitate the placing of a bobbin on the support, a space being provided between the guide and the side of the pocket for the passage of the yarn coming from a bobbin in the bobbin-holder.

4. The combination of a bobbin-holder having an open upper side, a reserve bobbin-support above the bobbin-holder and withdrawable to discharge a bobbin into the bobbin-holder, a space being provided at one side of the support for the passage of the yarn coming from a bobbin in the bobbin-holder, and means to keep the reserve bobbin away from said space.

5. The combination of a bobbin-holder, a reserve-bobbin support above the bobbin-holder, a space being provided at one side of the support for the passage of the yarn

coming from a bobbin in the bobbin-holder, and means arranged for contact with the butt of the reserve bobbin for keeping the reserve bobbin away from said space.

6. In a bobbin-support, a pocket having an open forward end for the longitudinal insertion of a bobbin, said pocket being arranged to swing out from beneath the bobbin, and means to prevent the bobbin from following the pocket.

7. The combination of a bobbin-holder having an open upper side, and adapted to rotatably support a warp bobbin, a pivotally suspended pocket above the bobbin-holder, said pocket having an open forward end for the longitudinal insertion of a bobbin, said pocket being arranged to swing upwardly to discharge a bobbin into the open upper side of the bobbin-holder, and a stop to limit the downward movement of the pocket.

8. The combination of a bobbin-holder, and a bobbin-support located above the holder and slightly at one side of the holder to provide space for the passage of a running thread extending from a bobbin in the bobbin-holder, said support being withdrawable in a direction away from said side.

9. In a bobbin-holder, two parallel longitudinal members, a pocket carried by and extending longitudinally of said members, said pocket being arranged to support a bobbin extending longitudinally of said members, and means for pivotally supporting said members at one of their ends, said pocket being open at the end opposite to said pivotal support.

10. The combination of a bobbin-holder having an entrance, said bobbin-holder being arranged rotatably to support a full warp bobbin while the latter is being unwound, and being movable to dump the bobbin when unwound, and means for supporting a bobbin in position to gravitate into said entrance.

11. The combination of a bobbin-holder arranged rotatably to support a full warp bobbin while the latter is being unwound, and a bobbin-support arranged to discharge a bobbin into the bobbin-holder, said holder and support being structurally distinct and capable of independent relative movement.

12. The combination of a bobbin-holder having an entrance, said bobbin-holder being arranged rotatably to support a full warp bobbin while the latter is being unwound, and being movable to dump the bobbin when unwound, and a bobbin-support arranged to support a bobbin in position to gravitate into said entrance, said holder and support being structurally distinct and capable of independent relative movement.

13. The combination of two bobbin-supporting devices, one located above the other, and one slightly at one side of the other to

provide space for the passage of a running thread extending from a bobbin in the lower bobbin-supporting device.

14. The combination of two independent bobbin-supports, one below the other, the lower bobbin-support having an open upper side and being adapted rotatably to support a warp bobbin during the delivery of yarn therefrom, and the upper bobbin-support being arranged to discharge a bobbin into the open upper side of the lower bobbin-support.

15. The combination of two independent

bobbin supports, one below the other, the lower bobbin support having an open upper side and being adapted rotatably to support a warp bobbin during the delivery of yarn therefrom, the upper support being pivoted to discharge a bobbin laterally into the open upper side of the lower support. 15 20

In testimony whereof, I hereunto set my hand in the presence of two witnesses.

HOWARD D. COLMAN.
